(57) **CLAIM**

The ornamental design for an external enclosure, as shown and described.

DESCRIPTION

FIG. 1 is a perspective view of an external enclosure;

FIG. 2 is a front elevation thereof;

FIG. 3 is a rear elevation thereof;

FIG. 4 is a left side elevation thereof;

FIG. 5 is a right side elevation thereof;

FIG. 6 is a top plane view thereof; and,

FIG. 7 is a bottom view thereof.

The broken line showing of the environment is for illustrative purpose only and forms no part of the claimed design.
